To all whom it may concern:

Be it known that we, JOHN McCLURE, PENN DE BARTHE, and EARL S. R. BICKEL, respectively citizens of the United States and residents of the city of Philadelphia, county of Philadelphia, and State of Pennsylvania, have jointly invented a new, original, and ornamental Design for an Emblematic Manufactured Figure, of which the following is a specification, reference being had to the accompanying drawing, forming part thereof.

The figure is a plan view of an emblematic figure showing our new design for a badge.

The design comprises a shield on which is a bull's-eye having concentric circular areas colored white, blue and red respec-

We claim:

The ornamental design for an emblematic manufactured figure as shown and described.

In testimony whereof we have hereunto signed our names this 14th day of February, 1919.
